SHELVING FOR REFRIGERATORS

Charles Euclair Passmore, Long Beach, N. Y.

Application June 12, 1933, Serial No. 675,388

6 Claims. (Cl. 312—183)

This invention relates to refrigerators and has more particular reference to an improved construction and arrangement of the shelves or other supports for the contents and, while not restricted thereto, the invention is primarily designed for use in connection with electric, gas or other equivalent mechanical refrigerators although the same may be adapted to ice chests or other forms of refrigerator cabinets.

0 The invention broadly aims to provide an improved rotary shelving for refrigerators, the construction and arrangement being such as to render the articles supported thereby more readily accessible so that the same may be reached with 5 greater facility and more expeditiously than heretofore, thus reducing to a minimum the length of time which the refrigerator door is open when emplacing articles in and removing the same from the refrigerator cabinet and thereby resulting in a substantial saving in the cost of operating the refrigerator.

The invention resides more particularly in a shelving arrangement, for refrigerators, in which the shelves are mounted for turning movement 5 on a vertical axis, the construction of the refrigerator cabinet and the arrangement of the shelving being such as not only to avoid any loss of shelf area but rather to increase the same.

In its principal application to electric refrigerators of the type which include an individual motor driven freezing unit, the invention comprehends a shelf turning means which is so constructed and connected with the motor which operates the freezing unit as to be driven thereby 5 to effect the turning movement of the shelves either automatically upon each opening of the refrigerator cabinet door or optionally by a manually controlled actuator, after the door is opened.

10 The invention further embodies a refrigerator shelf turning means, in combination with mechanism interposed between said means and the freezing unit motor, which mechanism may be so inter-connected with and controlled by the 15 refrigerator cabinet door as to render the shelf turning means inactive upon the ordinary operation of the motor for driving the freezing unit or if desired, the shelves may turn whenever the motor is in operation, but which mechanism is 20 such as to permit the motor to simultaneously operate the freezing unit and the shelf turning means.

The invention further contemplates, in a motor driven shelving for refrigerators, a shelf construction which is such that the article support-

ing portion thereof may be manually arrested in its movement without burning out or otherwise damaging the motor and, where a plurality of shelf units are driven from a common motor, the arrangement is such that the movement of any one or more of the article supporting portions thereof may be manually arrested without affecting the operation of the remainder of the units and which construction also functions to avoid breaking of containers or spilling of their contents by automatically arresting the movement of the supporting portion of the shelves, in event such containers are so placed thereon as to interfere with or obstruct the free movement of the supporting portions of the units.

15 The invention further embodies a refrigerator shelving in which the supporting portions of each shelf unit, as well as the complete units, may be readily and completely removed from the cabinet for cleansing, repairs, adjustments, replacements 20 or any other purposes.

Other objects in view are to provide a refrigerator shelving of the indicated character embodying comparatively few and simple parts, which parts are not complicated in construction so that 25 they may be economically produced, assembled and incorporated in a refrigerator cabinet and which shelving possesses the requisite strength and durability to withstand ordinary usage to which it may be subjected, but which, if damaged, 30 may be inexpensively repaired, serviced and maintained in working condition and which shelving furthermore is highly efficient for its intended purpose.

With the above recited and other objects in 35 view, reference is now made to the following specification and accompanying drawings in which there is disclosed, by way of example, a preferred embodiment of the invention, while the appended claims are intended to cover variations 40 and modifications thereof which properly fall within the spirit and scope of the invention.

In the drawings:

Fig. 1 is a front view of a refrigerator with the 45 door in open position and equipped with an improved shelving constructed in accordance with the present invention, parts being broken away and shown in section to disclose the underlying structure.

Fig. 2 is a horizontal sectional view there-through taken approximately on the line indicated at 2—2 in Fig. 1.

Fig. 3 is a diagrammatic side view of the shelf driving mechanism and control means therefor,

the refrigerator cabinet being shown in broken lines.

Referring to the drawings by characters of reference, A designates the body of a refrigerator cabinet which, in the present disclosure, is of the type which includes an individual motor driven compressor B for controlling the freezing unit C located within the cabinet body. The refrigerator shown, includes the usual fixed or stationary upper shelf D and one or more rotary shelf units designated generally by the reference character E, two shelf units being shown in the present disclosure.

Each shelf unit includes a rotary carrier designated by the reference character 9, the carrier being in the form of a flat disc like member having peripheral gear teeth 10, and a central hub portion 11, which hub portion has a concentric bearing 12 mounted to turn on a spindle 13 which protrudes upwardly from a hub 14, provided with laterally projecting spider arms 15 removably supported from the opposite side walls of the cabinet body A. The hub portion 11 is also provided with an upstanding concentric stud constituting a centering element or trunnion 16. The carrier member 9 is also provided with circumferentially spaced upstanding bearing lugs 17 adjacent its outer marginal edge and is provided with a plurality of perforations or openings 18 to permit of circulation of air therethrough and a wire netting 19 or other suitable material covers the openings to prevent the catching of the fingers therein and possible damage thereto.

Each shelf unit further includes a shelf member for supporting the articles which is designated generally by the reference character 20 and which is preferably made up of an annular woven wire body portion 21, an inverted cup-shaped concentrically arranged hub portion 22 and an annular rim portion 23 having an upstanding flange 24 at its outer marginal edge. The inverted cup-shaped hub portion 22 is of a size to fit over the centering trunnion 16 of the carrier member in such a manner that the trunnion may turn freely with reference thereto while the rim portion 23 is designed to rest on the lugs 17 of the carrier member whereby the shelf supporting member is supported by the carrier in a horizontal plane and ordinarily for turning movement with said carrier member on a vertical axis.

In order to provide means for turning the carrier and shelf member of each unit, a vertical shaft 25 is located in the cabinet body A adjacent one of the rear corners thereof and said shaft is provided with pinions 26 meshing respectively with the peripheral gear teeth 10 of the carrier members of the units. In the present disclosure the lower end of the shaft 25 extends into a compartment or housing space F arranged under the cooling compartment of the cabinet body A.

Obviously, rotary motion may be imparted to the shaft 25 in any desired manner or by any means desired, but in the present instance, the motor driven shaft 27 of the compressor unit B is employed which through the medium of reducing gearing in the gear box 28 imparts the desired speed of rotation to a shaft 29 protruding from the gear box and connected with the shiftable element 30 of a clutch. The other fixed element 31 of the clutch is secured to a shaft 32 which is operatively connected with the pinion shaft 25 for turning the same. As illustrated, the shaft 32 has secured thereto a beveled pinion 33 meshing with a beveled gear 34 on a counter-shaft 35 and a worm pinion 36 on said counter-shaft

meshes with a worm wheel 37 secured to the pinion shaft 25.

In order to provide means for controlling the turning of the pinion shaft 25 and shelf units so that the same will be turned only when the cabinet door G is open and at the option of the person removing articles from the cabinet or emplacing the same therein, the feed line of the motor driven compressor unit B including the conductors 40 and 41 has arranged in the conductor 41 a pair 1 of switches 42 and 43, the former being connected by a lead-in branch wire 44 to the conductor 41 and by an outlet branch wire 45 to the other side of the unit B. The other switch 43 has an outlet wire 46 connected to the other side of the unit B 1 through the usual thermostatically controlled breaker switch 47. The switches are controlled by a shift rod 48 which extends in a direction from the front to the rear of the refrigerator cabinet and which is normally urged outwardly by 2 means of a spring 49 so that the actuator lug 50 thereof is disposed out of contact with the switch button 51 of the switch 43, thus breaking the circuit at this point but engaging a collar 52 on the rod 48 with the terminal 53 of a foot lever 54 2 which is fulcrumed as at 55 and arresting the forward movement of the shift rod in this position due to the fact that a heavier spring 56 engages with the foot lever 54 and prevents further forward movement of the shift rod. The shift rod 3 is connected at 57 with the upper end of a clutch shifting fork 58 fulcrumed at 59, the arrangement being such that the shifting of the shift rod 48 under the action of the spring rod 49 will not swing the shifting fork 58 a sufficient distance to 3 engage the clutch elements 30 and 31, due to the fact that the collar 52 is arrested in its movement by engaging the terminal 53 of the foot pedal. As illustrated, the upper arm portion 60 of the shifting fork 58 is not permitted to move a sufficient distance, in this position of the shift rod, to engage with the actuator button 61 of the switch 42. However, when the foot pedal 54 is pressed inwardly in the direction indicated by the arrow in Fig. 3 against the action of the heavier spring 4 56, it will be obvious that the spring 49 will shift the shift rod further forwardly to engage the upper arm 60 with the actuator button 61 of the switch 42 thereby closing the circuit through wire 41, lead-in branch wire 44 and outlet wire 45 5 while the breaker switch controlled wire 46 is rendered inactive by the opening of the switch 43. Obviously, when the door G of the refrigerator cabinet is closed, it engages with a button 62 at the outer end of the shift rod and pushes the rod 5 48 rearwardly and engages the lug 50 with the actuator button 51 of the switch 43. The circuit through the switch 42 to the unit B is broken but the circuit is made or completed through the switch 43 to the thermostatically controlled 60 breaker switch 47. If desired, in addition to the foot lever or pedal 54, a finger button 63 may be employed which is connected by a push rod 64 to the terminal of the upper arm 65 of a lever 65 fulcrumed at 66, the lower arm 67 of which is 65 connected with the rear of the shift rod 48.

As illustrated, in Fig. 1, the shelf member 20 of one of the units E has mounted thereon for manually turning movement, a rack 72 which is provided with compartments of pigeon holes to 70 receive eggs or other articles. The refrigerator cabinet body A is also provided with electric lamps 73 located in the various subdivisions thereof for illuminating the shelves and contents.

From the foregoing it will be apparent that the 75

utilization of the motor power of the motor driven compressor unit of the refrigerator in no way interferes with its usual function except to momentarily render said unit B inactive when the 5 refrigerator door is open so that the rotary shelves will not be driven except at the option of the person using the refrigerator. It will also be apparent that there is no harm done to the compressor unit by momentarily setting the same into 10 operation when the same is not functioning in order to utilize its motive power for turning the shelves.

It will also be observed that by supporting the members 20 in the manner described, the same 15 may be grasped and arrested in their movement without retarding or stopping the rotation of the carrier member 9 which continues to rotate so as not to burn out or otherwise damage the winding of the motor. Likewise, the free or floating arrangement of the shelf members 20 serves to avoid 20 breakage of containers or spilling of their contents by automatically arresting the movement of the shelf members in event such containers are so placed thereon as to interfere with or obstruct 25 the free movement of the members 20.

In order to enclose and conceal the toothed edge of the carrier member 9, an arcuate channel shaped guard 70 is arranged thereover. In order to prevent articles supported by the shelves from 30 falling or being pushed off of the shelf into the corner spaces, wall sections 71 are provided above each shelf unit which extend from the forward open front of the box and around and in close proximity to the marginal flanges 24 of the shelf 35 members 20.

In some instances, such as in gas or other refrigerators, which are not provided with a motor or even in those having motors, a separate motor may be used for revolving the shelves, in which 40 event the clutch may be dispensed with. Furthermore, if desired, the freezing unit motor may be permanently connected with the shelves for revolving the same whenever the motor is active and in this case, control means similar to that 45 described, will be employed for rendering the freezing unit motor active to turn the shelves when the cabinet door is opened.

What is claimed is:

1. In a device of the class described, a cabinet 50 body, a door, a rotary shelf mounted within the body for turning movement on a vertical axis, a motor adapted to be operably connected with the shelf unit for turning the same on its axis, clutch means for coupling the shelf unit with the motor when the door is opened and adapted 55 to be uncoupled by the closing of the door, and means including an element of the clutch means for shifting the clutch to coupled relation and for rendering the motor active when the door is 60 open.

2. A refrigerator including in combination, a cabinet body having a door and a motor driven freezing unit, a rotary shelf unit mounted therein for turning movement on a vertical axis, 65 mechanism for transmitting motion to the shelf unit to turn the same on its axis, coupling means for operatively connecting the motor of the freezing unit with said mechanism, means operable by and with the coupling means for rendering the motor inactive when the door is opened, and means including an element of the clutch 70 means for simultaneously rendering the coupling and motor active when the door is open.

3. A refrigerator including in combination, a

cabinet body having a door and an electric motor for driving the freezing unit thereof; a rotary shelf unit mounted therein for turning movement on a vertical axis, mechanism for transmitting motion thereto from said motor, a 5 clutch for operatively coupling said mechanism to the motor, a normally open switch in the motor circuit and a common manually operable means for rendering the clutch active and for actuating said switch to close the motor circuit, 10 a second switch in the motor circuit, means operable by the refrigerator door when closed, for closing the motor circuit through said second switch and for breaking the motor circuit 15 thereby, when the door is opened.

4. In combination, an air circulating cabinet; one or more air-passing spiders horizontally supported in said cabinet and each providing a central anti-friction bearing; a turn-table for each said spider having air passage openings 20 and being rotatably mounted on said central anti-friction bearing; each said turn-table having a central upstanding shelf-centering hub and outwardly positioned upstanding friction drive shelf-supports; power operated means for rotating each said turn-table relatively to its spider; and a rotatable friction driven shelf of 25 open work formation for each said turn table, having a central cap for centering upon said hub and a circular friction track for riding on 30 said shelf-supports, whereby free circulation of air through each shelf is permitted and each shelf may be held against rotation and whereby friction driven rotation may be effected with 35 minimized friction loss.

5. In combination, an air circulating cabinet; one or more air-passing spiders horizontally supported in said cabinet and each providing a central anti-friction bearing; a turn-table for each said spider having air passage openings 40 and being rotatably mounted on said central anti-friction bearing; each said turn-table having a central upstanding shelf-centering hub and outwardly positioned upstanding friction drive shelf supporting means; power operated 45 means for rotating each said turn-table relatively to its spider; and a rotatable friction driven shelf of open work formation for each said turn-table, having a central cap for centering upon said hub and circularly disposed friction driven means to rest on said shelf supporting means, whereby free circulation of air through each shelf is permitted and each shelf may be held against rotation and whereby friction driven rotation may be effected with mini- 55 mized friction loss.

6. In combination, an air circulating cabinet having an openable door giving limited access to the interior of said cabinet; one or more frames permitting the free passage of air and 60 fixed in said cabinet and providing an anti-friction turn-table bearing; a perforated turn-table supported, centered and rotatable in a horizontal plane and upon said anti-friction bearing; an electric motor having mechanical 65 means for connecting it with said turn-table to rotate the same; electric leads for said motor; and two electric switches for said leads one openable and closable manually at will while the other is automatically closed by the opening 70 of said door and is automatically opened by the closing of said door.
